FOOT BATH

Charles M. G. Van Dijck, Antwerp, Belgium

Application March 14, 1952, Serial No. 276,610

4 Claims. (Cl. 4—182)

1

This invention relates to bathing apparatus which may be employed as foot baths.

An important object of the invention is to provide a bathing apparatus including a tub, having a discharge port and housing a grid structure of liquid spraying conduits which, when actuated by the occupant's body, either automatically closes or opens the port.

Another important object is to provide, in such a grid structure, for the discharge from the conduits of one or more liquids, without mixing the liquids prior to discharge.

A further important object is to provide, in a bathing tub, a structure which will cause a spray of liquid within the tub followed, if desired, by a turbulence in the sprayed liquid filling the tub.

Yet another important object is to provide a novel pedal associated with the grid structure for aiding in actuating the latter.

Other objects and advantages of the invention will be apparent during the course of the following detailed description of the invention, taken in connection with the accompanying drawing, forming a part of this disclosure and in which drawing:

Fig. 1 is a perspective view of the new bathing apparatus, portions of the walls of the tub thereof being broken away so as to better illustrate the grid structure and other parts within the tub.

Fig. 2 is a vertical longitudinal section of a manifold of the grid structure, substantially on the line 2—2 of Fig. 1.

Fig. 3 is a vertical longitudinal section of another manifold of the grid structure, substantially on the line 3—3 of Fig. 1.

Fig. 4 is a vertical section of the grid structure, substantially on the line 4—4 of Fig. 1.

Fig. 5 is a vertical section of the central portion of the grid structure with the structure depressed and a discharge port closed.

Fig. 6 is an enlarged vertical transverse section of two pipes of the grid structure, substantially on the line 6—6 of Fig. 1.

In the drawing, wherein for the purpose of illustration is shown a preferred embodiment of the invention and wherein similar reference characters designate corresponding parts throughout the several views, the letter A designates the new bathing apparatus as a whole and comprising a receptacle or tub B; liquid distributing means C within the receptacle or tub B; means D to conduct one liquid to the means C; means E to conduct another liquid to the means C; means F to move the means C to open or close

2

a discharge port of the receptacle or tub B; and means G to assist in moving the means C.

The bathing apparatus A may be employed as a foot bath and may be portable or fixed.

Preferably, the receptacle or tub B is rectangular with two opposite upstanding walls 10 and 11 joining two opposite upstanding walls 12 and 13 which four walls, with a bottom wall 14, define a chamber 15 having an upwardly opening mouth. Legs 16 may be provided to elevate the bottom wall above any suitable conventional supporting surface (not shown), so that the bottom wall is substantially horizontal. The receptacle or tub may be of sheet metal and be provided, in the bottom wall 14, with a discharge or drainage port 17 communicating with a conventional discharge conduit 18 carried beneath the wall 14.

The liquid distributing means C comprises a movable or rockable grid structure of two substantially paralleling, elongated, spaced-apart major manifolds 20 and 21, a minor manifold 22 associated with the manifold 20 and a plurality of elongated spaced-apart conduits connecting one or another of the manifolds, as will be described, and forming (1) a grid-like connection of the manifold, (2) liquid conduits, (3) partial supports for the means G, and (4) means to cooperate with a part of the means F so as to prevent accidental shifting of the grid structure in two directions.

As shown particularly in Figs. 1 and 2 the manifolds 20 and 22 comprise two tubular sections with the major manifold 20 provided with one end wall 25 and may have an opposite end wall 26, while the minor manifold 22 may be of the same diameter as that of the manifold and have a wall 27 at one end and be joined, at its other end, to the end wall 26 as by welding, soldering or the like. Thus, there is provided a chamber 28 in the manifold 20 and a chamber 28a in the manifold 22.

In the manifold 20 are a plurality of spaced apart outlet openings or ports 29 disposed in a row longitudinally of the manifold 20 and an outlet opening or port 30 in the manifold 22, with the axes of all the openings 29 and 30 intersecting a straight line, paralleling the longitudinal axis of the two manifolds 20 and 22. In each manifold 20 and 22 is an upwardly-opening inlet opening or port 31 and 32 respectively.

The manifold 21, shown particularly in Figs. 1 and 3, is a tubular section provided with end walls 35 and 36 and its overall length is substantially the same as the combined overall lengths

of the manifolds 20 and 22. It is provided with a plurality of spaced-apart outlet openings or ports 37 and an inlet opening or port 38 arranged in a straight row longitudinally of the manifold 21. The positions of the openings 37 are staggered with respect to the openings 29 but the opening 38 is directly opposite the opening 30 when the three manifolds are associated as will be described.

As may be seen in Figs. 1, 2 and 3 there are provided a plurality of elongated substantially paralleling, spaced-apart conduits or laterals 40 and 41, connecting the manifolds 20 and 21 and with the alternate conduits 40 opening into the ports 29 and closed by the wall of the manifold 21 at their other ends, while the conduits 41 open into the ports 37 and are closed at their other ends by the wall of the manifold 20. Preferably, except for the end conduit 49 which has one row of spaced apart discharge openings 42, the other conduits 40 have two rows of spaced-apart discharge openings 42, all arranged to discharge liquid outwardly and upwardly.

There is an elongated conduit or lateral 43 which opens to the ports 30 and 38 and may be welded or soldered to the manifolds 21 and 22.

The means D to conduct one liquid to the means C may comprise an upstanding conduit 45 opening at its lower end into the inlet opening 31 and joined at its other end to a flexible (as rubber) tube or conduit 46 which is joined to a conduit 47 in which is interposed a conventional hand operated valve 48. The conduit 47 may lead to a suitable supply of liquid.

Except that the means E conducts liquid to the manifold 22 of the means C by way of an upstanding conduit 50 opening to the inlet opening 32, the means E is preferably like the means D and includes a flexible tube 51, conduit 52 and valve 53.

Means F to move the means C to open or close the discharge port 17 is shown particularly in Figs. 1, 3, 4 and 5, and includes the spaced-apart bearings 55 of Figs. 1, 4 and 5 each of which comprises a bearing block 56 secured in any approved way as by welding, soldering or the use of screws, to the bottom wall 14 and having an upwardly-opening arcuate recess to receive a portion of the manifold 20, and a cap 57 having an arcuate recess to receive an adjacent portion of the manifold 20, with securing means 58 as nut and bolt assemblies to detachably secure the block 56 and cap 57 together, so that the manifold 20 may rotate in the bearings 55. It will be noted in Fig. 1 that the width of each bearing 55 is very slightly less than the nearest distance two adjacent conduits 41 are spaced apart and, thus, the bearings 55 and these adjacent conduits prevent longitudinal shifting of the manifold 20 and consequently, shifting of the entire grid structure in two directions.

The means F also includes the resilient structure of Figs. 1, 3 and 4. This structure preferably comprises two expansion spiral springs 59 with their lower ends seated in the sockets of upstanding socketed members 60 secured to the bottom wall beneath the manifold 21 and their upper ends extending into the sockets of socketed members 61 secured to the manifold 21. These members 61 may include clamps to be removably clamped about the manifolds 21 by means of nut and bolt assemblies 62. Thus, the springs 59 urge the manifold 21 upwardly to swing in an arc with the rest of the grid structure.

The means F also includes a closure or plug

63 shown in Figs. 1, 3 and 5, secured to the central part of the manifold 21 to extend downwardly therefrom and with the discharge port 17 disposed in the path of travel of the free or lower end portion of this closure as the manifold 21 descends, so that this port may be closed, as in Fig. 5.

It has been found very desirable to provide the means G to assist in moving the means C. The means G preferably comprises two pedals or foot sole-receiving members, each of which has an upwardly slanting portion 65 with its lower end having two arcuate recesses to accommodate the upper portions of two adjacent conduits 40 and 41, a foot engaged portion 66 extending at one end from the upper end of the portion 65, and a portion 67 slanting downwardly from the other end of the portion 66, between two adjacent conduits 40 and 41 to rest upon the bottom wall 14. These means G may be disposed as most convenient for the occupant of the new bathing apparatus since they may be moved nearer together or farther apart.

In use, the occupant or attendant opens either or both valves 48 and 53. If only the valve 48 is opened, the liquid (preferably under pressure) from the conduit 47 will flow into the manifold 20 and conduits 40 to be discharged from the discharge openings 42 in the latter. At this time (or at a desired time) the occupant places his feet upon the portions 66 of the means F depressing the end of the grid structure containing the plug or closure 63 until the plug closes the discharge port 17. Several steps may follow. Firstly, the liquid discharge from the discharge openings 42 sprays the feet of the occupant then, as the tub or receptacle B fills up, the liquid immerses the feet and the liquid discharged from the openings 42 causes a turbulence of the liquid, in the nature of swirls, eddies and bubbling effects, all beneficial to certain treatments of the feet.

Of course, if the occupant raises his feet from the portions 66, the springs 59 will cause the manifold 21 to rise and the plug 63 to open the port 17 to discharge the liquid in the tub B, but this will not cause stoppage of the discharge from the discharge openings 42 of the conduits 40 and the steps may be repeated. If it is desired a different liquid or a liquid at a different temperature than that discharged from the conduits 40, be employed in conjunction with or instead of the discharged liquid mentioned, then the valve 53 may be opened and liquid, preferably under pressure from the conduit 52 will flow into the manifold 22, through the imperforated conduit 43, into the manifold 21 and through the conduits 41 to be discharged from their openings 42.

It is now clear that the degree of turbulence of the liquid may be increased by opening both valves 48 and 53, or they (either of them) may be rhythmically opened and closed to provide surges of the liquid.

Various changes may be made to the form of the invention herein shown and described without departing from the spirit of the invention or scope of the claims.

What is claimed is:

1. A foot bath including a stationary tub having a bottom wall provided with a tub drain port; rockable means within the tub to receive liquid and discharge the liquid into the tub including a plurality of spaced-apart rigid conduits; a foot sole-receiving member having an upwardly-extending portion provided with a pair of arcuate

recesses accommodating portions of two adjacent conduits, a foot sole-receiving portion extending from an end thereof to form an obtuse angle and a portion extending downwardly from the other end thereof, disposed between said two adjacent conduits, and with its lower end resting upon said bottom wall; and means operable upon rocking of said rockable means to selectively open and close said port.

2. A foot bath including a stationary tub having a tub drain port; rockable means within the tub to receive liquid and discharge the liquid into the tub including a grid structure having two elongated manifolds and a third manifold rigid with one of said elongated manifolds, a plurality of elongated conduits, having discharge ports intermediate their ends, opening into only one of said elongated manifolds and rigid with both of said elongated manifolds, a plurality of elongated conduits having discharge ports intermediate their ends, opening into only the other of said elongated manifolds and rigid with both manifolds, and a conduit rigid with said third manifold and the other of said elongated manifolds opening into said third manifold and said other of said elongated manifolds; and means operable upon rocking of said rockable means to selectively open and close said port.

3. A foot bath including a stationary tub having a drain port; rockable means within the tub to receive liquid and discharge the liquid into the tub including a grid structure having two elongated manifolds and a third manifold rigid with one of said elongated manifolds, a plurality of elongated conduits, having discharge ports intermediate their ends, opening into only one of said elongated manifolds and rigid with both of said elongated manifolds, a plurality of elongated conduits having discharge ports intermediate their ends, opening into only the other of said elongated manifolds and rigid with both manifolds, and a conduit rigid with said third manifold and the other of said elongated manifolds opening into said third manifold and said other of said elongated manifolds, means rockably supporting said rockable means including a bearing for one of the elongated manifolds and having a width very slightly less than the shortest distance sep-

rating two adjacent conduits; and means operable upon rocking of said rockable means to selectively open and close said port.

4. A foot bath including a stationary tub having a tub drain port; rockable means within the tub to receive liquid and discharge the liquid into the tub including a grid structure having two elongated manifolds and a third manifold rigid with one of said elongated manifolds, a plurality of elongated conduits, having discharge ports intermediate their ends, opening into only one of said elongated manifolds and rigid with both of said elongated manifolds, a plurality of elongated conduits having discharge ports intermediate their ends, opening into only the other of said elongated manifolds and rigid with both manifolds, and a conduit rigid with said third manifold and the other of said elongated manifolds opening into said third manifold and said other of said elongated manifolds; means rockably supporting said rockable means including a bearing for one of the elongated manifolds and having a width very slightly less than the shortest distance separating two adjacent conduits, and an expansion spiral spring with one end bearing against the other of said elongated manifolds and with the other end of said spring bearing against said tub; and means operable upon rocking of said rockable means to selectively open and close said port including a plug for said port carried by the last-named elongated manifold and with said port disposed in the path of travel of said plug when said grid structure is rocked to compress said spring.
